UNITED STATES PATENT OFFICE.

WILLIAM L. R. EMMET, OF SCHENECTADY, NEW YORK, ASSIGNOR TO GENERAL ELECTRIC COMPANY, A CORPORATION OF NEW YORK.

TURBINE BUCKET-WHEEL.

No. 901,430.

Specification of Letters Patent.

Patented Oct. 20, 1908.

Application filed March 17, 1908. Serial No. 421,757.

To all whom it may concern:

Be it known that I, WILLIAM L. R. EMMET, a citizen of the United States, residing at Schenectady, county of Schenectady, 5 State of New York, have invented certain new and useful Improvements in Turbine Bucket-Wheels, of which the following is a specification.

The present invention relates to bucket 10 wheels for elastic fluid turbines and has for its object to improve their construction, particular reference being made to increasing their rigidity, decreasing their weight and reducing the cost of manufacture.

15 In the accompanying drawings which illustrate one of the embodiments of my invention, Figure 1 is a partial view in elevation of a bucket wheel; Fig. 2 is a partial axial section thereof; Fig. 3 is a partial section taken on line 3—3 of Fig. 4; Fig. 4 is an enlarged detail view showing the bucket securing means; Fig. 5 is a perspective view of a bucket; and Fig. 6 a perspective view of a space block.

25 In order to fully appreciate the conditions under which the bucket wheels of my invention operate, a general statement as an example will be beneficial. The wheel shown is about twelve feet six inches in diameter on 30 the pitch line of the buckets and weighs between five and six thousand pounds, the weight varying somewhat with the length of the buckets. The buckets when in operation travel through space at about four hundred and sixty feet per second, or over five 35 miles a minute. With buckets of moderate size in such a wheel there is a force due to centrifugal action of about six hundred pounds per bucket tending to separate it 40 from the wheel. This force increases with an increase in weight of each bucket and also with an increased shaft speed. The buckets rotate between stationary parts, such for example as the nozzle and the intermediate 45 buckets arranged in a row between the rows of wheel buckets. The clearance between the relatively rotating parts varies with different conditions, .06" to .12" not being unusual. The figures above mentioned have 50 been given merely as examples and are not to be considered as limitations.

1 indicates a cast steel hub for the wheel having an annular flange 2 extending perpendicular to the axis of the shaft. This flange 55 is provided with a plurality of radial arms 3

that serve to brace the flat disks 4 located on opposite sides thereof. I prefer to use separate arms as shown rather than a solid member in order to decrease the weight of the wheel as much as possible. The disks 4 are 60 made of commercial rolled plate of the desired thickness. These plates are roughly sheared to size and are then put in a boring mill and bored to the required dimension, and the periphery turned to the desired 65 diameter. The inner faces 5 of the disks are made flat, while the outer faces 6 are turned off so that the peripheral portions are somewhat thinner than the portions adjacent the hub. Between the annular flange 2 and each 70 of the disks is a shoulder 7 formed on the flange and entering a corresponding recess in the disk. I prefer to form the shoulder on the flange rather than on the disk because this arrangement does not require the turning off of any considerable amount of metal on the disks and hence the latter can be made thinner than would be the case if the shoulder was formed on the disk and seated in a 75 groove formed in the annular flange 2. 80 These disks are attached to the flange and arms by axially-extending rivets 8. By using shoulders 7 as described, the shearing strains on the rivets are decreased, and the strains 85 due to centrifugal force are transmitted directly to the hub.

The hub is provided with a bore 9 of suitable diameter and also with key-ways or slots 10 to receive the keys that secure the wheel on the main shaft. The wheels are usually 90 forced on the shaft under considerable pressure and in order to remove them from the shaft and also to handle them by a crane when removed it is necessary to provide means whereby they can be readily handled 95 without injury. To this end the flange 2 is provided with screw-threaded openings 11, four being shown, to receive eye-bolts or other devices to which the hooks on the crane can be attached or to which other 100 means can be attached for seating the wheel on the shaft or pulling it off. Registering with the screw-threaded openings are holes 12 in the plates of slightly larger diameter so that the strains due to the use of the eye-bolts are transmitted directly to the hub 105 rather than to the disks. If the holes in the disk were screw-threaded and the eye-bolts by accident were not firmly seated in the flange then when force was exerted on the 110

eye-bolts they might so strain the rivets as to weaken the wheel as a whole which thereafter would be a source of danger.

At a point near the periphery of each disk 5 and on the inner face a rectangular groove 13 is provided in which is seated an annular spacing member 14. This member is provided with a series of openings 15 to admit steam to the interior of the wheel so that the 10 internal temperature will be the same, or substantially the same, as the external, and so that the steam pressures on all parts will be equal. When the wheel is mounted on a vertical shaft a second set of holes or openings 16 is provided, through which any water due to condensation can be discharged from the interior to the exterior of the wheel. The annular member 14 is preferably made up in sections of convenient length. To hold 20 the member or spacing device 14 in place, and to prevent the disks from separating at their peripheries due to any cause a number of axially-extending rivets 17 are provided. It is to be noted that these rivets are located 25 inside of the member 14 where they are out of the path of the moving steam and hence do not offer any resistance to rotation. I have found in actual practice that it sometimes happens that a workman in heading over 30 these rivets will strain the disks in such a manner that the part between the member 14 and the flange and arms will be slightly dished or concaved, which throws the buckets slightly out of line. To obviate this, rectangular blocks 18 are provided through 35 which the rivets pass. These blocks may be of any suitable shape, and should be long enough to prevent the wheels from buckling or dishing, as above described, when the rivets 40 17 are headed.

Attached to the inner face of each disk is a steel base or back 19 containing a dove-tailed groove 20 to receive the dove-tailed ends 21 of the buckets 22. The buckets are separated from each other by space blocks 23. The bases are secured to the inner faces of the 45 disks by axially-extending rivets 24. In order to reduce the shearing strains on these rivets an annular groove 25 is turned in the inner face of each disk, which groove is of rectangular cross-section and receives an annular shoulder or projection formed on the base, 19 of each row of buckets. I prefer to form the shoulder 26 on the base rather than on 50 the disk because it decreases the amount of machine work and permits me to use disks that are thinner in the rough state than would be the case if the shoulders were formed thereon. The bases for the buckets 55 are made up in segments of suitable length, as clearly shown in Fig. 3. By reason of this construction I am able to mount them in place without difficulty and also to repair the wheel in case the buckets in one segment are 60 injured or are defective, due to any cause.

The outer ends of the buckets are provided with covers 27 which are made in segmental sections and are secured in place by tenons 28 formed integral with the outer ends of the buckets.

The distance between the two rows of wheel buckets is determined by the width of the intermediate buckets 29. These buckets have to be of a width sufficient to properly turn the steam as it passes from one row of buckets to the other. The shape of these buckets is very similar to that of the wheel buckets, but their position is reversed in order to reverse the direction of the steam flow. In order to make the wheels as stiff as possible against deflection in an axial direction at or near the periphery they should be separated as much as possible. This separation in a wheel having two rows of buckets as shown is limited by the width of the intermediate buckets. It is undesirable to make the width of the intermediate buckets unduly great for the reason that it increases the losses in the turbine due to friction, and also because it increases the overall length of the machine, the latter having a direct bearing on the cost of construction. I obtain the greatest separation possible between the disks without, however, increasing the overall dimensions of the turbine by mounting 95 the bucket bases on the inner faces of the disks, as best shown in Fig. 4. By reason of this construction I am able to provide a wheel that is exceedingly rigid while at the same time it is not made unduly heavy considering the amount of work it has to perform. It is to be noted that the outer faces of the disks are perfectly smooth which has the advantage of decreasing the rotation losses due to the movement of the wheel on 100 a body of steam more or less dense. By using steel for the parts as described the expansion and contraction of the parts under temperature changes will be equal, thus preventing one part working loose from another 105 part or parts.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure 110 by Letters Patent of the United States, is,—

1. In a bucket wheel, the combination of a hub having an annular flange, disks attached to opposite sides of the flange, a row of radial buckets for each disk, a separate base for each row of buckets that is attached to the inner face of its supporting disk, and means for uniting the disks to reduce the 115 tendency to distortion.

2. In a bucket wheel, the combination of 120

a hub having an annular flange, disks attached to opposite sides of the flange, a shoulder between each disk and the flange for transmitting strains from the former to the latter, a row of radial buckets for each disk, bases therefor which engage the inner faces of the disks, a shoulder between each base and its disk to transmit strains from the former to the latter, and axially-extending means that clamp the bases to the disks.

3. In a bucket wheel, the combination of a hub having an annular flange, disks attached to opposite sides thereof, a row of buckets for each disk, bases for the buckets which are attached to the inner faces of the disks, an annular perforated member which separates the disks by a fixed distance near their peripheries, axially-extending devices for holding the disks against said member, and means preventing the said devices from distorting the disks in the course of manufacture.

4. In a bucket wheel, the combination of a hub having an annular flange, radial arms attached thereto which form spacers, disks located on opposite sides of the flange and arms, a shoulder between the flange and each disk to transmit strains from the latter to the former, means clamping the disks to the flange and arms, a row of radial buckets for each disk, a base for each row of buckets that engages the inner face of the disk, an annular shoulder between each base and the inner face of the disk to transmit strains from the former to the latter, means clamping each base to the inner face of the disk, and means for holding the disks at a fixed distance apart near their peripheries.

5. In a bucket wheel, the combination of a cast steel hub having an annular flange and arms radiating therefrom, rolled steel plates of disk form attached to opposite sides of the

flange and arms, rivets which pass through the flange, arms and disks to unite them, shoulders between the disks and flange to transmit strains from the former to the latter and reduce shearing strains on the rivets, a row of radial buckets for each disk, separate steel bases in which the inner ends of each row of buckets are anchored, rivets for securing each base to the inner face of its supporting disk, a shoulder between each base and the inner face of each disk to reduce the shearing strains on the rivets, and means separate from the bases for uniting the disks near their peripheries.

6. In a bucket wheel, the combination of a hub having an annular flange and arms extending radially therefrom, annular shoulders on opposite sides of the flange, plates made in the form of disks located on opposite sides of the flange and grooved on their inner faces to receive annular shoulders on the flange and bucket bases, the said disks decreasing in thickness toward their peripheries, radial buckets, bases therefor which have annular shoulders which enter the grooves in the disks, means that unite the disks and secure them to the flange and arms, and means that secure the bases on the disks.

7. In a bucket wheel, the combination of a hub member having screw-threaded openings therein to receive eye-bolts, disks attached to the sides of the hub member which are provided with openings registering with those in said member but of greater diameter, and buckets carried by each of the disks.

In witness whereof, I have hereunto set my hand this 10th day of March, 1908.

WILLIAM L. R. EMMET.
